UNITED STATES PATENT OFFICE.

HARRY W. HAMILTON, OF DETROIT, MICHIGAN, ASSIGNOR TO HAMILTON MANUFACTURING COMPANY, OF INDIANAPOLIS, INDIANA, A CORPORATION OF INDIANA.

FUEL-FEED SYSTEM.

1,306,377.

Specification of Letters Patent. Patented June 10, 1919.

Application filed July 2, 1917. Serial No. 178,324.

To all whom it may concern:

Be it known that I, HARRY W. HAMILTON, a citizen of the United States, residing at Detroit, in the county of Wayne and State 5 of Michigan, have invented a new and useful Fuel-Feed System, of which the following is a specification.

It is the object of my invention to provide an improved type of petrol pump for supplying fuel to internal combustion engines, especially in automobiles, as when the main supply tank is lower than the carburetor; to make such pump simple in structure, easy to manufacture, and reliable in operation; 15 and in particular to guard against simultaneous connection to the source of vacuum and to the atmosphere, to provide a positive closure for the valve between the upper and lower chambers, and to prevent flooding by 20 the action of the same float which controls the atmosphere and vacuum connections.

The accompanying drawings illustrate my invention. Figure 1 is a vertical central section through a petrol pump embodying my invention, being taken substantially on the line 1—1 of Fig. 4; Fig. 2 is a partial section and partial elevation through the upper part of my petrol tank, the section being taken on the line 2—2 of Fig. 4; Fig. 3 is a 25 detail of the vacuum and atmosphere valves, and their operating mechanism, showing both valves closed; Fig. 4 is a horizontal section through my petrol pump, being taken substantially on the line 4—4 of Fig. 1; Fig. 30 35 5 is a diagrammatic view showing the relative arrangement of my petrol pump, the main supply tank, the carburetor, and the engine of an automobile.

In many if not most modern automobiles, the fuel tank 10 is normally lower than the carburetor 11 by which the explosive mixture supplied to the engine 12 is made, such main tank 10 usually being at the rear of the automobile chassis 13, as indicated in Fig. 5. In order to supply fuel to the carburetor 11 from this lower supply tank 10, I mount my petrol pump 14 at a point higher than the carburetor 11, conveniently under the automobile hood 15, and interconnect this petrol pump with the main supply tank 10 by a pipe 16, with the carburetor 11 by a pipe 17, and with a source of vacuum, such as the intake manifold 18 by a pipe 19, so as to utilize the vacuum in such intake mani-

fold to lift the fuel from the main tank 10 55 into the petrol pump, whence it is allowed to flow to the carburetor 11 by gravity. My present invention is not in this broad idea, but in the particular petrol pump and its connections.

My petrol pump has a central horizontal plate 20 which supports the whole pump and is provided at its rear edge with attaching feet 21 by which it may be mounted, as on the dash 23 of the automobile. Two metal 65 cup-shaped shells 24 and 25 are attached to the central plate 20 on the upper and lower sides of the latter, with their open ends against such plate, conveniently being fastened by bolts 26 which pass through outwardly extending flanges 27 at the open ends of such shells and through the intermediate plate 20 near the edge thereof. The central plate and these shells form an upper chamber 28 and a lower chamber 29. The pipe 70 75 17 passes through the lower end of shell 25 to communicate with the lower part of chamber 29. The edge of the plate 20 is provided at points approximately opposite the feet 21 with two hollow projections 30 80 and 31, which are threaded for connection to the pipes 16 and 19 respectively, and is also provided with an opening 32 direct to the atmosphere. The openings in the hollow projections 30 and 31 and the opening 85 32 communicate by passages in the plate 20 with three pipes 33, 34, and 35 respectively, which project upward from plate 20 into the chamber 28.

At the upper end of the pipe 33 is a valve 90 fitting 36 on which is pivotally mounted a lever 37 carrying at one end a valve 38 which co-operates with the valve fitting 36 under certain conditions to close the end of the pipe 33. The other end of the lever 37 is 95 forked to project on the two sides of the float stem 39 of the float 40, on which float stem is a collar 41 which when the liquid level in the chamber 28 rises beyond a pre-determined level co-operates with the lever 100 37 to move the latter in a counter-clockwise direction (Fig. 2) so as to push the valve 38 against the fitting 36 and close the pipe 33. Thus the float 40 closes the valve 38 to shut off positively the flow of the fuel into the 105 chamber 28 from the supply tank 10 when the fuel level in such chamber reaches a pre-determined height, which pre-determined

height is above the normal maximum, as might occur when the automobile is descending a hill and the normally lower tank 10 is at a higher level than is the chamber 28 by reason of the tilting of the automobile. The valve 38 is only operated under abnormal conditions, and is wholly a safety device. The stem of the valve 38 preferably carries an umbrella deflector 42, which deflects downward the fuel discharged from the pipe 33 and prevents such fuel from being thrown into the upper part of the chamber 28 and splashing around therein.

Mounted on the upper ends of pipes 34 and 35 is a valve fitting 45, which has two downwardly presented valve seats 46 and 47 which communicate with the pipes 34 and 35 respectively. Two needle valves 48 and 49 coöperate with these respective valve seats, and are carried by two separate and independent bell crank levers 50 and 51, mounted on separate pivot pins 52 and 53 in the valve fitting 45. The closing movements of the valves 48 and 49 are limited by their engagement with the valve seats 46 and 47, and their opening movement is limited by the engagement of the bell crank levers 50 and 51 with shoulders 54 and 55 on the valve fitting 45. A lever 56 is also pivotally mounted on the valve fitting 45, on a pivot pin 57, and is connected at one end to the upper end of the float stem 39, the lower end of which is guided in a hole 58 suitably provided in the central plate 20. Two sets of springs 60 and 61 extend from two intermediate points on the lever 56 to the two bell crank levers 50 and 51 respectively, being connected to the latter at the opposite ends thereof from those which carry the valves 48 and 49. In the arrangement shown, each of these sets of springs comprises two springs, projecting on opposite sides of the valve fitting 45, and connected at opposite ends of cross bars on the lever 56 and the bell crank levers 50 and 51. The points of connection of the sets of springs 60 and 61 to the lever 56 and the bell crank levers 50 and 51, and the relative locations of the shoulders 54 and 55 with relation to valve seats 47 and 46 respectively, are such that as the lever 56 is moved the lines of pull of the two sets of springs 60 and 61 pass through the pivot points 52 and 53 successively and not simultaneously, making such passage first for the springs associated with that one of the two valves 48 and 49 which is open so as to produce a closing of such valve before the other or closed valve is opened. By this construction, the two valves 48 and 49 are never open simultaneously, so that the chamber 28 is never connected at the same time to both the source of vacuum and to the atmosphere.

The central plate 20 is perforated to provide a passageway 65 between the upper

and lower chambers 28 and 29. The lower end of this passageway 65 is controlled by a plate valve 66, which is guided in its movements by a yoke 67. The plate valve 66 is connected by a chain 68 to a projection 70 from the lever 56, so that when the float 40 reaches its lower limit of movement the valve 66 is brought to closed position positively, thus positively breaking the connection between the upper and lower chambers 28 and 29 when such float reaches its lowermost position and thereby causes an inflow of fuel into the upper chamber 28 as hereinafter explained. In order that the fuel in the lower chamber 29 may be under atmospheric pressure when the valve 66 is closed, the central plate 20 is provided with an opening 69 communicating with the top of the chamber 29 and with an upwardly extending pipe 70 on the outside of the shell 24, the upper end of this pipe 70 being above the highest possible fuel level in the upper chamber 28 and preferably having its upper end formed as a return bend to prevent the clogging of the pipe by settling dust. The upper end 90 of the pipe 70 is open to the atmosphere.

In operation, the engine 12 maintains a certain suction in its intake manifold. When the valve 48 is open, this suction is also developed in the chamber 28, but is prevented from being transmitted to the chamber 29 by the valve 66, which when once closed is held closed by this suction while the float 40 rises so long as the valve 48 remains open. When this suction is developed in the chamber 28, it causes fuel to flow from the main supply tank 10 through the pipe 16, the hollow projection 30, and the pipe 33, into the chamber 28. As this fuel flows into the chamber 28, it lifts the float 40, (the valve 66 nevertheless being held closed by the suction,) and thereby moves the lever 56, until the line of pull of the set of springs 60 passes the pivot point 52, whereupon the valve 48 is snapped from open to closed position. For a moment, the valves 48 and 49 are then in the position shown in Fig. 3. The closing of the valve 48 disconnects the chamber 28 from the source of vacuum, but for a very short period of time after the closing of the valve 48 the fuel continues to flow into the chamber 28 from the pipe 33, by reason of the momentum of the fuel and of the static condition of partial vacuum which exists in the chamber 28 momentarily even though the valve 48 is closed. Therefore, immediately after the valve 48 is closed, the continued upward movement of the float 40 and the continued swinging of the lever 56 moves the line of pull of the set of springs 61 past the pivot point 53, thereby producing a snapping open of the valve 49. This opening movement of the valve 49 occurs immediately after the closing of the valve 48, but

not until the valve 48 has been closed, so that the valves 48 and 49 are not both open at once. This connects the chamber 28 to the atmosphere, to admit atmospheric pressure into such chamber. The pressure in the chamber 28 then immediately rises to atmosphere, and the inflow of fuel from the pipe 33 stops, and by reason of atmospheric pressure conditions in the chamber 28 the valve 66 drops open. Fuel now flows by gravity from the upper chamber 28 into the lower chamber 29, and up into the riser pipe 70. As fuel is used by the engine, and is thereby drawn from the chamber 29, the fuel from the chamber 28 flows through the passage 65 into the chamber 29 to take the place of that which is drawn off for use, and the fuel level in the chamber 28 falls. The float 40 likewise falls, to swing the lever 56 in the opposite or clockwise direction. Eventually, as the float 40 approaches its lowermost limit of movement, it swings the line of pull of the set of springs 61 past the pivot point 53, thereby causing the valve 49 to snap to closed position to shut off the connection of the chamber 28 to atmosphere, and immediately thereafter, as the float 40 continues to fall though very slightly, swings the line of pull of the set of springs 60 past the pivot point 52 to snap the valve 48 open and thereby connect the chamber 28 to the source of vacuum. At substantially the same time that the valve 48 is snapped open, the valve 66 is positively brought to closed position, thereby closing the communication between the upper and lower chambers. The vacuum condition now produced in the chamber 28 causes the inflow of fuel thereinto from the pipe 33 as has been explained, and produces a repetition of the cycle just described. This is repeated as often as required by the demands of the engine, and a constant supply of fuel is thereby maintained for the carburetor. In addition, there is no time when the upper chamber 28 is connected simultaneously with both the source of vacuum and the atmosphere.

If for any reason the inflow of fuel into the upper chamber 28 continues after the valve 48 is closed, as because of a forward tilting of the automobile as when descending a hill, the continued rise of the float 40 closes the valve 38 and prevents flooding, as already explained.

I claim as my invention:

1. A petrol pump for fuel feed systems, comprising a casing divided into upper and lower chambers, float mechanism controlled by the liquid level in the upper chamber for controlling the fluid pressure condition therein to produce intermittent feeding of fuel by suction into said upper chamber, and a valve controlling the connection between said two chambers, said valve being con-

trolled jointly by said float and by the pressure condition in the upper chamber and being arranged so that it is closed by the action of the float when the latter reaches its lower limit of movement but is otherwise free from the float and has a normal tendency to open.

2. A petrol pump for fuel feed systems, comprising a casing divided into upper and lower chambers, float mechanism controlled by the liquid level in the upper chamber for controlling the fluid pressure condition therein to produce intermittent feeding of fuel by suction into said upper chamber, and a valve controlling the connection between said two chambers, said valve being connected to said float so that it is positively moved to its seat when the float reaches its lower limit of movement but otherwise being free from the float and having a normal tendency to open and when closed being held to its seat by the suction created by a low pressure condition in the upper chamber until the float reaches its upper limit of movement and causes a higher pressure condition in said upper chamber.

3. A petrol pump for fuel feed systems, comprising a casing divided into upper and lower chambers, float mechanism controlled by the liquid level in the upper chamber for controlling the fluid pressure condition therein to produce intermittent feeding of fuel by suction into said upper chamber, and a valve controlling the connection between said two chambers, said valve being connected to said float so that it is positively moved to its seat when the float reaches its lower limit of movement but otherwise being free from the float and having a normal tendency to open.

4. A petrol pump for fuel feed systems, comprising a casing divided into upper and lower chambers, a fuel supply pipe leading to the upper chamber, connections from said upper chamber to a source of vacuum and to the atmosphere, a float in the upper chamber and responsive to the liquid level therein, said float co-operating with said connections to the source of vacuum and to the atmosphere to produce alternately relatively low and high pressure conditions in said upper chamber when the float reaches its lower and upper limit of movement respectively, and a valve controlling the connection between the upper and lower chambers and connected to the float so as to be positively closed thereby when the float reaches its lower limit of movement but otherwise being free from the float and having a normal tendency to open, said connection between the float and the valve permitting the valve to be held closed by the low pressure condition in the upper chamber while the float rises.

5. A petrol pump for fuel feed systems,

- comprising a casing divided into upper and lower chambers, a fuel supply pipe leading to the upper chamber, connections from said upper chamber to a source of vacuum and to the atmosphere, a float in the upper chamber and responsive to the liquid level therein, said float co-operating with said connections to the source of vacuum and to the atmosphere to produce alternately relatively low and high pressure conditions in said upper chamber when the float reaches its lower and upper limit of movement respectively, and a valve controlling the connection between the upper and lower chambers and connected to the float so as to be positively closed thereby when the float reaches its lower limit of movement but otherwise being free from the float and having a normal tendency to open.
6. A petrol pump for fuel feed systems, comprising a casing divided into upper and lower chambers, a fuel supply pipe leading into said upper chamber from a normally lower source of fuel supply, a float controlled by the liquid level in the upper chamber, said upper chamber having a connection adapted to lead to a source of suction, mechanism operated by said float and controlling said connection to the source of suction to produce alternately relatively high and low pressure conditions in said upper chamber upon normal rise and fall of liquid level in said upper chamber and thereby to produce intermittent feeding of fuel into said upper chamber through said supply pipe, and a valve controlling said supply pipe and loosely associated with said float so that it is not affected by normal rise and fall of liquid level in said upper chamber but is closed by said float upon abnormal rise of said liquid level.
7. A petrol pump for fuel feed systems, comprising a feed conduit from a lower source of fuel supply to a carburetor and including a chamber at a higher level than either the carburetor or the fuel source, connections from said chamber to a source of vacuum and to the atmosphere, a float controlled by the liquid level in said chamber, mechanism operated by said float and controlling said connections to said source of vacuum and the atmosphere to produce alternately relatively high and low pressure conditions in said chamber upon normal rise and fall of liquid level in said chamber, and a valve controlling said conduit between said fuel source and said chamber, said valve being loosely associated with said float so that it is not affected by normal rise and fall of liquid level in said upper chamber but is closed by said float upon abnormal rise of said liquid level.
8. In combination, a liquid chamber having connections to a source of vacuum, to a supply of liquid, and to a device which is
- to be supplied with such liquid, valves controlling the first and second of said connections respectively, and a single float controlled by the liquid level in said chamber and controlling both of said valves, said float operating to close the said two valves successively and at different fuel levels upon rise in the liquid level in said chamber and to permit them to open successively and at different fuel levels upon fall in said fuel level.
9. A petrol pump for fuel feed systems, comprising a casing providing upper and lower chambers, a valve controlling the connection between said two chambers, a valve controlling the connection of said upper chamber to a source of fuel supply, valve mechanism for controlling the pressure condition in said upper chamber, each of said valves having movements independent of the others, and a single float controlling all of said valves.
10. A petrol pump for fuel feed systems, comprising a casing providing upper and lower chambers, a valve controlling the connection between said two chambers, a valve controlling the connection of said upper chamber to a source of fuel supply, a single float controlling both of said valves, and float-controlled valve mechanism controlling the pressure condition in said upper chamber, each of said valves having movements independent of the others.
11. In combination, a liquid chamber having connections to a source of vacuum, to a supply of liquid, to the atmosphere, and to a device which is to be supplied with such liquid, two independent valves controlling said first and third connections, and means controlled by the liquid level in said chamber for closing the valve in the first connection and opening the valve in the third connection successively upon rise in said liquid level and for closing the valve in the third connection and opening the valve in the first connection successively upon fall in such liquid level.
12. In combination, a liquid chamber having connections to a source of vacuum, to a supply of liquid, to the atmosphere, and to a device which is to be supplied with such liquid, two independent valves controlling said first and third connections, and means controlled by the liquid level in said chamber for closing the valve in the first connection and opening the valve in the third connection successively upon rise in such liquid level.
13. In combination, a liquid chamber having connections to a source of vacuum, to a supply of liquid, to the atmosphere, and to a device which is to be supplied with such liquid, two independent valves controlling said first and third connections, and means controlled by the liquid level in said chamber

ber for closing the valve in the third connection and opening the valve in the first connection successively upon fall in such liquid level.

- 5 14. In combination, a liquid chamber having connections to a source of vacuum, to a supply of liquid, to the atmosphere, and to a device which is to be supplied with such liquid, two independent valves controlling 10 the first and third connections respectively, and a float controlled by the liquid level in said chamber and controlling said valves oppositely but so that one always closes before the other opens.
- 15 15. In combination, a liquid chamber having connections to a source of vacuum, to a supply of liquid, to the atmosphere, and to a device which is to be supplied with such liquid, valves controlling the first and third 20 connections respectively, and a float controlled by the liquid level in said chamber and controlling said valves oppositely but so that one always closes before the other opens, said two valves being provided with 25 means for causing them to operate with a snap action.
16. In combination, a liquid chamber having connections to a source of vacuum, to a supply of liquid, to the atmosphere, and to 30 a device which is to be supplied with such liquid, two independent pivotally mounted valves controlling the first and third connections, a float-operated member controlled by the liquid level in said chamber, a spring 35 connecting each of said pivotally mounted valves to said float-operated member and arranged so that the line of spring action is moved to opposite sides of the pivot point of such valve upon movement of said float- 40 operated member as the liquid level rises and falls to operate said valves oppositely, said springs being arranged so that the one which is connected to the valve which is open is moved past the pivotal point of such valve 45 to produce closing of such valve before the spring of the closed valve is moved past the pivotal point of such valve to produce opening thereof.
17. In combination, a liquid chamber having 50 connections to a source of vacuum, to a supply of liquid, to the atmosphere, and to a device which is to be supplied with such liquid, two independent pivotally mounted valves controlling the first and third connections, a float-operated member controlled 55 by the liquid level in said chamber, a spring connecting each of said pivotally mounted

valves to said float-operated member and arranged so that the line of spring action is moved to opposite sides of the pivot of 60 such valve upon movement of said float-operated member as the liquid level rises and falls to operate said valves oppositely.

18. In combination, a liquid chamber having connections to a source of vacuum, to a supply of liquid, and to a device which is to be supplied with such liquid, valves controlling the first and second of said connections respectively, and a single float controlled by the liquid level in said chamber and controlling both of said valves, said float operating to close both of said valves upon rise to successively higher levels and to open both of said valves in reverse order upon fall to successively lower levels of the liquid 70 level in said chamber.

19. In combination, a liquid chamber having connections to a source of vacuum, to a supply of liquid, and to a device which is to be supplied with such liquid, valves controlling the first and second of said connections respectively, and a single float controlled by the liquid level in said chamber and controlling said valves at different liquid levels. 80

20. A petrol pump for fuel feed systems, 85 comprising a casing providing upper and lower chambers, a valve controlling the connection between said two chambers, a valve controlling the connection of said upper chamber to a source of fuel supply, valve 90 mechanism for controlling the pressure condition in said upper chamber, and a single float controlling all of said valves, said float acting on said second valve at a higher fuel level than that at which it acts on the other 95 valves.

21. A petrol pump for fuel feed systems, comprising a casing providing upper and lower chambers, a valve controlling the connection between said two chambers, a valve 100 controlling the connection of said upper chamber to a source of fuel supply, a single float controlling both of said valves, and float-controlled valve mechanism controlling the pressure condition in said upper chamber, said float acting on said second valve at a higher fuel level than that at which it acts on the first valve. 105

In witness whereof I have hereunto set my hand at Indianapolis, Indiana, this 20th 110 day of June, A. D. one thousand nine hundred and seventeen.

HARRY W. HAMILTON.
